US00D887266S

(12) **United States Design Patent** (10) Patent No.: **US D887,266 S**
(45) Date of Patent: **** Jun. 16, 2020**

(54) **STORAGE CONTAINER LID**

- (71) Applicant: **SWIMC LLC**, Cleveland, OH (US)
- (72) Inventors: **Richard D. Hudson**, North Olmsted, OH (US); **James J. Johnson**, Lake Milton, OH (US); **Gustavo A. Morales**, Brunswick, OH (US); **Edward Ray Goodwin, Jr.**, Westlake, OH (US); **Michael C. Lambertson, Jr.**, Aurora, OH (US); **Charles T. Buckel, Jr.**, Valley City, OH (US)
- (73) Assignee: **SWIMC LLC**, Cleveland, OH (US)
- (**) Term: **15 Years**
- (21) Appl. No.: **29/683,067**
- (22) Filed: **Mar. 11, 2019**

Related U.S. Application Data

- (63) Continuation of application No. 29/645,014, filed on Apr. 23, 2018, now Pat. No. Des. 847,650, which is a continuation of application No. 29/559,224, filed on Mar. 25, 2016, now Pat. No. Des. 818,830.

(57) **CLAIM**

The ornamental design for a storage container lid, as shown and described.

DESCRIPTION

FIG. 1 is a perspective view of a storage container lid showing our new design;
FIG. 2 is a front view of the storage container lid illustrated in FIG. 1;
FIG. 3 is a rear view of the storage container lid illustrated in FIG. 1;
FIG. 4 is a left side view of the storage container lid illustrated in FIG. 1;
FIG. 5 is a right side view of the storage container lid illustrated in FIG. 1;
FIG. 6 is a top view of the storage container lid illustrated in FIG. 1; and,
FIG. 7 is a bottom view of the storage container lid illustrated in FIG. 1.
The broken lines in the drawings showing the storage container lid illustrate the portions of the storage container lid that form no part of the claimed design.

1 Claim, 4 Drawing Sheets
